(57) **CLAIM**

The ornamental design for a dispensing carton as shown and described.

DESCRIPTION

FIG. 1 is a front perspective view of a dispensing carton, showing my new design.

FIG. 2 is a left elevation view of the dispensing carton of FIG. 1, the right elevation view is a mirror image.

FIG. 3 is a front elevation view of the dispensing carton of FIG. 1.

FIG. 4 is a rear elevation view of the dispensing carton of FIG. 1.

FIG. 5 is a top plan view of the dispensing carton of FIG. 1, the bottom plan view is a mirror image; and,

FIG. 6 is a plan view of the dispensing carton of FIG. 1 shown in an unfolded configuration.

The evenly-spaced broken lines in the drawings depict portions of the dispensing carton that form no part of the claimed design. The evenly-spaced broken lines shown in the interior of the dispensing carton depict environmental structure only and form no part of the claimed design.
